UNITED STATES PATENT OFFICE.

CHARLES N. TUCKER, OF NEW BEDFORD, MASSACHUSETTS, ASSIGNOR TO HOPEDALE MANUFACTURING COMPANY, OF MILFORD, MASSACHUSETTS, A CORPORATION OF MASSACHUSETTS.

PICKER-STICK CHECK MOTION.

Application filed March 7, 1921. Serial No. 450,176.

To all whom it may concern:

Be it known that I, CHARLES N. TUCKER, a citizen of the United States, residing at New Bedford, in the county of Bristol and State of Massachusetts, have invented certain new and useful Improvements in Picker-Stick Check Motions, of which the following is a specification, reference being had to the accompanying drawings.

10 This invention relates to improvements in looms, and particularly to a picker stick check.

The general object of my invention is to provide an improved check which is particularly reliable in action, simple in construction and durable in service, which is easy to operate and easy to put on and take off.

15 A further object is to provide a construction of this character so constructed as to provide a frictional surface carried by the laybeam and with which the member carried on the picker stick engages when the picker stick is retracted.

20 And a further object is to provide a device of this character which will keep the picker stick from splitting.

25 And another object is to provide a device of this character which can be put on or taken off in a few minutes and which may be placed on either end of the lay and which is readily adjustable.

30 Other objects will appear in the course of the following description.

35 My invention is illustrated in the accompanying drawings, wherein:—

Figure 1 is a fragmentary side elevation of the laybeam of a loom, the picker stick thereof and my picker stick check applied thereto;

40 Figure 2 is a fragmentary end elevation of the laybeam and picker stick with my improvement applied;

45 Figure 3 is a sectional view through the picker stick and the supporting bracket 12, the check being illustrated in plan.

Referring to these drawings, 10 designates the laybeam of the loom and 11 the picker stick thereof. The picker stick and laybeam may be of any suitable character 50 and the picker stick operated in the usual manner. The particular construction of the laybeam and picker stick has nothing to do with my invention.

55 My improved picker stick check consists of two parts, one of which is mounted upon

the laybeam of the loom and the other upon the picker stick. The part mounted upon the laybeam of the loom comprises a downwardly and outwardly extending bracket 12 which is preferably formed of cast iron about $\frac{1}{2}$ thick, this arm or bracket 12 being disposed preferably all in one plane. The upper end of this bracket is formed with a slot 13 which extends, when the bracket is applied, approximately parallel to the upper face of the lay and the lower end of this bracket is formed with a rectangular notch 14. Mounted upon this bracket, as by means of the screw 15, bolt or like device, is a strip of metal, designated generally 16, which is bent to form a base 17 engaging upon the outer face of the lower end of the bracket and through which the screw 15 passes, the metal being then bent laterally and then longitudinally, as at 18, and riveted to the inner extremity of this portion 18 is a strip of thin metal 19 having rearwardly divergent, resilient arms 20. The outer faces of these arms are covered with a strip of leather 20^a riveted to the arms or attached in any other suitable manner.

Mounted upon the picker stick 11 is a yoke 21 which is rectangular in form and embraces the picker stick and extends outward beyond the picker stick to form arms 22 or lugs between which is disposed a wooden block 23 which is designed to bear against the outer face of the picker stick. A bolt 24 passes through the arms or ears of the yoke and through this wooden block and holds the block in position.

Attached to the yoke 21 is an upwardly extending, loop-shaped member 24. The loop of this member is rectangular in form and the two opposing faces of the loop are lined internally with strips of leather 25. The material of the loop is extended downward, as at 26, to form a shank which is inserted between the yoke 21 and the picker stick and is held in engagement with the yoke by a rivet 27. The opposing faces of the loop 24 are spaced from each other a distance slightly less than the spaces between the outer faces of the divergent arms of member 19, and in the operation of this device, when the picker stick moves outward, the relatively narrow end of the check member 16 will enter the loop and the loop will move outward, gradually pressing the spring arms 19 toward the portion 18. 110

Thus it will be seen that the arms 20 together form a yielding male member upon which the loop 24 or female member is impaled to check the picker stick in its outward movement. This checking action will be gradual and frictional in character. By reason of the elongated slot 13, the arm 12 or bracket may be adjusted longitudinally upon the lay so as to dispose the member 16 in any desired position to check the outward movement of the picker stick. The yoke 21 may be also vertically adjusted upon the picker stick to any desired position so as to secure the entrance of the checking member 16 into the loop 24 when the picker stick is retracted.

It will be obvious that this device is very easily put in place and that it may be applied to either end of the laybeam or to both ends of the laybeam as may be desired, and that the yoke 21 keeps the picker stick from splitting at the point where the yoke is applied. The block 22, which is preferably of wood, keeps the yoke snug against the picker stick so that it will not get loose while the stick is thrown. The adjustability of the parts adds very greatly to the value of this device, as by its means the device may be applied to a great many different forms of looms and at any time adjusted to suit running conditions. The parts from which the check are made are relatively few and easily procured, while in making the straps which form the frictional surface of the check, any scraps of leather strap such as are commonly used in looms for various purposes can be utilized. It will be seen that no oiling is required for this device, that there is nothing to break or get out of order, and that the check is so constructed as to be thoroughly effective in practice.

I claim:—

1. The combination with the laybeam of a loom and a picker stick operating therewith, of means for checking the picker stick comprising a bracket mounted upon the laybeam, a yielding and elastic member carried by the bracket and extending in the direction of motion of the picker stick and having a friction surface, and a member carried upon the picker stick and moving therewith and having a friction surface co-acting with the friction surface on the first named member as the picker stick is retracted.

2. In a loom, the combination with the laybeam and picker stick thereof, of means for checking the outward motion of the picker stick comprising a loop-like member mounted upon the picker stick and having opposed approximately parallel surfaces, and a checking member carried by the laybeam and having two outwardly divergent portions, each of said portions being resilient and compressible toward the other

portion, said portions being adapted to be engaged by said loop-like member and the resilient portions forced inward upon the outward movement of the picker stick.

3. The combination with a loom having a laybeam and a picker stick, means for checking the picker stick comprising a bracket mounted upon the laybeam and extending downward and toward the outer end of the beam, a member mounted upon said bracket and formed to provide two aligning portions, said portions converging toward the middle of the loom and diverging outward and being faced with friction material, each of said portions being resilient and being compressible toward the other portion as the picker stick is retracted.

4. A picker stick check for looms comprising a bracket adapted to be applied to the laybeam of the loom, a check mounted upon the bracket and comprising two connected portions converging toward the middle of the loom and diverging toward the outer end of the beam, each of said portions being resilient and both of said portions being faced with frictional material, and a loop-like member adapted to be clamped upon the picker stick of the loom and having parallel, vertically extending portions covered on their inner faces with frictional material and adapted to receive said first named portions carried by the bracket.

5. A picker stick check comprising a bracket in the form of an arm, a check member detachably mounted upon the lower end of the bracket and formed of a metal strip constructed to provide outwardly diverging, resilient portions converging toward the middle of the loom, the outer faces of said portions having a facing of frictional material, a yoke adapted to embrace the picker stick and form a lug on each side thereof, a block supported between said lugs and adapted to bear against the picker stick, and a vertically elongated loop-like portion carried by the yoke and having two parallel sides faced with frictional material adapted to receive between them the check portion carried by said bracket.

6. In a loom, the combination with a laybeam and a picker stick therefor, of a bracket mounted upon the laybeam, the upper end of the bracket being slotted parallel to the beam whereby the bracket may be adjusted, a check member carried by the lower end of the bracket and formed with a metallic strip extending toward the picker stick and then parallel to the plane of movement of the picker stick and toward the middle of the loom, rearwardly diverging, resilient arms attached to the inner end of said strip and faced with frictional material, a yoke embracing the picker stick and vertically adjustable thereon and formed to provide ears projecting outwardly from the

picker stick, a picker stick engaging block disposed between said ears, and a vertically extending, loop-like member carried by said yoke and extending upward against the side 5 of the picker stick and having vertically disposed parallel portions lined with leather, said loop adapted to receive between it the convergent end of the check member as the picker stick is retracted to thereby 10 check the movement of the picker stick.

7. The combination with the laybeam of a loom and a picker stick operating therewith, of means for checking the picker stick comprising a member supported by the laybeam and including a pair of outwardly divergent, resilient arms faced on their outer faces with frictional material, and a member carried upon the picker stick and moving therewith and having a loop-like portion 15 formed to provide two oppositely disposed parts between which the rearwardly diverging arms extend in the operation of the loom as the picker stick is retracted.

8. A picker stick check for looms having, 20 in combination, relatively movable male and

female members, the former being resilient and elastic and adapted to receive the latter as the picker stick is retracted to check the outward motion of the picker stick.

9. A picker stick check for looms having, 30 in combination, a yielding and elastic male member connected to the loom frame and a rigid female member connected with the picker stick and adapted to be impaled upon the male member to check the outward movement of the picker stick.

10. A picker stick check for looms having, 35 in combination, cooperating male and female members, the one adapted to be secured to the picker stick and the other to the loom frame, one being elastic and yielding as the one member is impaled upon the other.

11. A picker stick check for looms having, 40 in combination, cooperating members, one being elastic and yielding and adapted to enter the other which is rigid and unyielding to act as a check on the picker staff.

In testimony whereof I hereunto affix my signature.

CHARLES N. TUCKER.
